CLAIM

The ornamental design for a double feeding basin for pets, as shown and described.

DESCRIPTION

FIG. 1 is a top plan view of a double feeding basin for pets, showing my new design;

FIG. 2 is an enlarged left side view thereof;

FIG. 3 is an enlarged right side view thereof;

FIG. 4 is a rear elevation view thereof; and,

FIG. 5 is a rear, top perspective view thereof.

The broken lines illustrate portions of the double feeding basin for pets that form no part of the claimed design.
